United States Patent

Des. 237,824
Patented Nov. 25, 1975

237,824

DUPLICATING CARVING MACHINE

Albert Kenneth Pagander, 4219 Linden Ave.,
Long Beach, Calif. 90807

Filed Aug. 3, 1973, Ser. No. 385,403

Term of patent 14 years

Int. Cl. D15—09

U.S. Cl. D55—1 A

The single figure is a perspective view of a duplicating carving machine showing my new design.

The broken line disclosure is for illustrative purposes only and forms no part of the claimed design.

I claim:

The ornamental design for a duplicating carving machine, as shown and described.
